(57) **CLAIM**

The ornamental design for a urinal basket, as shown and described.

DESCRIPTION

FIG. 1 is a front and top perspective view of a urinal basket showing my new design;

FIG. 2 is a top plan view thereof;

FIG. 3 is a rear perspective view thereof;

FIG. 4 is a side perspective view thereof; and,

FIG. 5 is a front perspective view thereof.

The broken lines shown in the drawings illustrate unclaimed environment, form no part of the claimed design, and are provided for context only.
